UNITED STATES PATENT OFFICE.

ALFRED F. MASURY, OF NEW YORK, N. Y., ASSIGNOR TO INTERNATIONAL MOTOR COMPANY, OF NEW YORK, N. Y., A CORPORATION OF DELAWARE.

RADIATOR FOR AUTOMOBILES.

1,271,191.

Specification of Letters Patent.

Patented July 2, 1918.

Application filed February 26, 1915. Serial No. 10,674.

To all whom it may concern:

Be it known that I, ALFRED F. MASURY, a citizen of the United States, residing in the borough of Manhattan of the city of New York, in the State of New York, have invented certain new and useful Improvements in Radiators for Automobiles, of which the following is a specification, reference being had to the accompanying drawings, forming a part thereof.

This invention relates to radiators for automobiles and is concerned particularly with that type of radiator in which air currents are established and maintained by means of a fan and are caused to pass over the water tubes and thereby cool the water before it passes to the cylinder jackets. In this type of radiator the tubes are arranged in bundles of substantially cylindrical outline and the fan is mounted within the bundles and in substantially co-axial relationship thereto, so that the cooling air travels into the space within the bundles in a direction parallel to the axis thereof and is there caught up by the revolving fan blades and thrown outwardly through the tubes in a direction radially thereto. By reason of the dispersion of the air in this manner, it will be evident that a radiator of this character will deprive the motor of the air which would otherwise pass thereover and have a cooling action, unless the radiator is so constructed as not to interfere with the natural supply of air to the motor. It is the principal object of this invention so to construct and mount the improved radiator that the motor will receive the entire supply of air which normally passes through the bonnet of a car while it is moving forward while it will, at the same time, force an ample supply of cooling air across the bundle of water tubes and so insure the effective cooling of these tubes at all times. A further object is to provide a radiator which shall perform the additional function of creating a constant draft through the body of the car about the driver's seat and particularly under the dash. This draft not only cools the space referred to and thereby dissipates the heat which normally rises under the dash, but also insures an adequate supply of cooling air for the water tubes. To realize the stated objects of the invention the improved radiator is mounted just forward of the dash and between it and the motor space so

that the fan is exposed both to the motor space and to the space behind the dash and takes its cooling air from the tubes from both sides thereof. This disposition of the radiator is especially effective in assisting the natural draft of air through the motor bonnet which is created normally by the forward movement of the car alone. The invention is further concerned with certain details of construction of the radiator whereby it is made very compact, inexpensive to manufacture, readily accessible for repair or replacement of parts and attractive in appearance. One embodiment of the invention will now be described with reference to the accompanying drawings in which—

Figure 1 is a fragmentary view, partly in vertical section and partly in side elevation of a portion of a car equipped with the improved radiator, and showing particularly the relation thereof to the motor bonnet and the driver's seat.

Fig. 2 is a detail view on an enlarged scale, partly in side elevation and partly in vertical section, of the improved radiator, the water tubes being broken out in the interest of clearness.

Fig. 3 is a detail view in elevation of the improved radiator, part of the casing therefor being broken away to show the disposition of some of the tubes, the view being taken from within the motor bonnet.

The automobile body *a* may have mounted on the forward end of its chassis *b* its motor *c*, which may be inclosed, as usual, by a motor bonnet *d*, the forward end of which may be open to permit the free inflow of air during the forward movement of the car. On the chassis *b* of the car or motor support *b'* thereof may be mounted the improved radiator, indicated generally at *e*, and having at its base suitable feet *e'*, through which and the motor support *b'* may be passed securing bolts *f*, whereby the radiator as a unit *100* may be demounted. In Fig. 3 the motor is omitted in the interest of clearness, but in Fig. 1 it is clearly shown as being secured to the underside of the member *b'* by the bolts. The radiator *e*, includes a casing *e²*, *105* the sides of which may be stamped up from a single sheet of metal or which may be built up of a front and back plate and exposed well sections *e³* in which is formed on each side, and of maximum area, an opening *e⁴* *110*

for the outflow of air as will appear later. The casing of the radiator may be strengthened as may be necessary by suitable angle plates g . Within the casing e^2 is built up 5 the radiator structure proper consisting preferably of two substantially semi-cylindrical bundles of water tubes h , the ends of which are expanded into plates i , each semi-cylindrical bundle of tubes with the end 10 plates forming a unitary and detachable section. The plates i are secured to water reservoirs k and l disposed respectively at the top and bottom of the radiator and formed with inclined sides to receive the 15 plates i , and detachable ends to permit access to the tubes h . These plates may be detachably secured to the flanged side walls of the reservoirs k and l by suitable bolts m . The upper reservoir k may be provided, as 20 usual, with a cap k' to permit the filling of the radiator, and with an inlet pipe k^2 through which the water passes from the jacket of the motor c through a duct c' , as will be understood. The lower reservoir l 25 also may carry an outlet passage l' through which the water may pass from the radiator to the jacket of the motor c through a suitable connection c^2 , thus completing the water circuit.

30 From the description given, it will be understood that the bundles of tubes h with the reservoirs k and l form an annulus, the space within which is exposed to the air on both sides of the radiator, that is, that with- 35 in the motor bonnet d and that within the dash of the car body a . The bundles of tubes h and the reservoirs k and l may be inclosed by the front and rear plates of the casing e^2 for the radiator, but these plates do not ex- 40 tend inwardly to a sufficient extent to cut off the free space within the annulus. Within this free space and substantially in the plane of the tubes h is mounted a suitable air fan which may be formed with a hub n 45 mounted on suitable bearings n' and carrying fan blades n^2 , which may be disposed in the most effective relationship to the hub. In practice it has been found desirable to have these fan blades n^2 extend substantially 50 tangential to the hub n , although it is to be understood that other arrangements may be used without departing from the invention. A simple and practical form of fan is illus- 55 trated and will be described in some detail.

60 The supporting shaft o of the fan may be conveniently mounted in diametrical brackets p and q which may be bolted to the end faces of the reservoirs k and l and on the outer faces of the end plates of the casing e^2 for the radiator. One of the brackets q is curved appreciably to receive the driving belt r for the fan and the driving pulley n^3 over which the belt passes. On the fixed shaft o is carried a sleeve o' on which are 65 formed recesses for the roller bearings o^2 ,

these bearings being embraced by race rings o^3 on which rests the tubular hub n proper for the fan. The surface of this hub, in the illustrated embodiment, is tapered from the middle in both directions, as shown by dotted lines at n^4 , in Fig. 2, and slotted at suitable intervals on its circumference to receive the fan blades n^2 , which may be detachably held in position by set screws n^5 . As the fan blades n^2 are of substantially the same width 70 as the bundles of tubes h and have their outer ends in juxtaposition to the inner tubes of these bundles, it will be understood that a very strong current of air will be thrown through these bundles of tubes when the fan 75 is rotated.

In the interest of safety, the exposed openings in the front and rear walls of the casing e of the radiator and the openings e^4 in the side walls e^3 thereof may be covered 80 with suitable wire mesh s which will prevent accidental injury through contact of a person with the revolving fan, will prevent the entrance of foreign objects into the casing and will afford a slight appearance to the 85 radiator.

Thus far, it has been sought only to describe the structure by which the objects of the invention are realized but it is to be remembered that of equal importance with 90 the structural features of the radiator is the disposition thereof with respect to the other parts of the car and the novel theory of operation on which the invention is based to a great extent. In the first place, a radi- 95 cal departure from known constructions is marked by the disposition of the radiator between the motor bonnet and the dash so that the fan is exposed to the air within the motor bonnet and to the air under the 100 dash and around the driver's seat. By reason of this disposition, the free passage of air into the space under the motor bonnet is not interfered with in any way so that the motor has the advantage of the receiv- 105 ing a full cooling action from this natural inflow during the forward movement of the car. In previous constructions this natural inflow of air to the motor has been inter- 110 ferred with. Again, this flow of air through the motor bonnet is enhanced by the im- 115 proved radiator and the full effect thereof received by the motor because of the dis- position of the fan at the rear of the motor and in free communication therewith. It 120 is to be noted, however, that the cooling of the water tubes h through the radial dis- 125 persal of the air received by the fan is not brought about entirely by that air which has passed through the motor bonnet but an equal supply of absolutely fresh air may be drawn in by the fan from the space under the dash of the car a , since the fan is not only exposed to the bonnet d but is also ex- 130 posed to the space around the driver's seat.

- This induced draft around the space of the driver's seat is highly desirable for other reasons than the cooling of the bundles of tubes *h* because this space under the dash usually becomes very warm, especially where fore-doors are used. The present invention, therefore, embodies means for cooling the forward end of the body *a* of the car. The action of the fan is such as to take all of the air which flows thereto from each side thereof in directions substantially parallel with the axis of the fan and to throw the air outward in a substantially radial direction and cause it to pass through the bundles of tubes *h* and out through the openings *e*⁴ formed in the side walls of the casing *e*² of the radiator. The air thus expelled will be somewhat warm after passing over the water tubes *h*, but this warm air at this part of the body *a* of the car will not be objectionable as the dash or cowl will throw it away from the body and the passengers in the car.
- As pointed out before, the improved radiator *e* may be detached as a unit by loosening the bolts *f* or, where desired, the radiator may remain in position on the motor support *b'* and be removed with the motor as a unit.
- In repair or replacement of any of the parts of the improved radiator, it will be clear that ready access is afforded thereto by removal of any one of the constituent parts of the casing *e*² of the radiator. By loosening the bolts *m* in any one of the
- plates *i* the plate with the tubes *h* may be detached readily from the abutting flanges of the inclined walls of the reservoirs *k*, *l*. Further, either one of the brackets *p*, *q* may be demounted by loosening its securing bolts *40* and the fan thereafter readily removed from the position within the bundles of tubes *h*. Modifications of the details of construction will suggest themselves to those skilled in the art, but all such modifications are to be deemed within the spirit of this invention provided they fall within the scope of the appended claim.
- I claim as my invention:
- A radiator for automobiles comprising a casing having its end and side walls perforated, water reservoirs, semi-cylindrical bundles of tubes secured to the reservoirs, plates into which the ends of the tubes are expanded, the reservoirs being provided with inclined and flanged side walls to receive said plates, means to secure the plates detachably to the flanges, a fan rotatably mounted within the bundles of tubes and in the plane thereof, and supports for the fan extending diametrically across the circular bundles and secured detachably to the outer sides of the radiator.
- This specification signed and witnessed this 24th day of February, A. D. 1915.
- ALFRED F. MASURY.
